MANIFOLDING

Louis C. Antrim, New York, N. Y., assignor to
 Autographic Register Company, Hoboken, N. J.,
 a corporation of New Jersey

Application March 12, 1932, Serial No. 598,378

10 Claims. (Cl. 197—126)

This invention relates to typewriting machines, and more particularly, to means for facilitating the making of multiple copies, and is an improvement on the invention described and claimed in my prior application, Serial No. 579,390, filed December 7, 1931.

In said application I have disclosed means for holding between worksheets superposed on the platen a transfer or carbon disk so that the latter will roll between the worksheets as the relative movement between the latter and the type mechanism occurs during the writing of a line.

There is also disclosed in said application means for causing the transfer disk to be raised and lowered as it rolls, so that all parts of the working margin of the disk will be used.

It has been found in practice that even though the transfer disk is raised and lowered relative to the line of writing so that the impressions follow an undulating line around the peripheral zone of the disk, if the line of writing happened to be shorter than the length of the circumferential working zone a segment of the disk will be left unconsumed, for, in rolling backward through the worksheets to begin a new line, the disk would be given substantially the same angular movement that it received in rolling forwardly. This unused portion of the disk would constitute a waste and unnecessary loss.

Further, if the major portion of the writing operations are performed at one side of the worksheets, the carbon copies made on the worksheets beyond said portion would be darker than the others because of the underlying segments of the transfer disks not having been used so much. The carbon copies would therefore have an unsightly appearance resulting from light impressions on one side and dark impressions on the other.

Likewise, this two-tone printing may occur when the carbon disk has shifted relative to the line of writing, as it may should it be temporarily removed from between the worksheets, for the adjustment of the latter, for instance, and then be replaced.

To avoid these disadvantages, the present invention provides means for holding the transfer disks against retrograde or backward rotation when the platen or type carriage, according to the kind of typewriter employed, is moved to position to begin a new line. In this way the first impressions of a new line on the transfer disk begin substantially where the last impressions of the previous line left off.

In the preferred form of this invention, this is

accomplished by providing a sort of ratchet connection between the transfer disk and the arm which carries it, and this ratchet connection is advantageously formed by a tooth or projection on the disk carrier adapted to engage one of a plurality of holes or other physical alterations provided in the transfer disk.

Other features and advantages will hereinafter appear.

In the accompanying drawings—

Figure 1 is a front elevation of a typewriter showing my invention applied thereto.

Fig. 2 is a diagrammatic view showing the relative movements of the transfer disk relative to the platen.

Fig. 3 is a sectional view through the platen of the typewriter, taken on the line 3—3 of Fig. 1, showing the relation between the worksheet strips and the carbon disks of the present invention.

Fig. 4 is a view of the end of the carbon-carrying arm showing the carbon disk of the present invention applied thereto, and held against retrograde movement by the fingers on the arm.

Fig. 5 is a view of the carbon-carrying arm itself.

Fig. 6 is a view of the carbon disk made in accordance with the present invention, showing it in the form at present preferred.

Fig. 7 is a transverse sectional view taken on the line 7—7 of Fig. 4, the tooth or projection on the carbon-carrying arm being located in one of the apertures or holes in the carbon disk.

Fig. 8 is a similar view, but shows the way in which the material of the disk flexes past the projection or tooth on the carbon arm when the disk is rotating forwardly.

Fig. 9 is a detail view of the means for causing the impressions of the transfer disks to follow an undulating line.

The typewriter shown in the accompanying drawings is of the kind having a cylindrical platen 10 mounted in a traveling carriage 11 so that various portions of the platen may be carried across a printing point 12 at which the type bars 13 strike through an inking ribbon 14. The platen supports, in writing position, worksheets 15 which may be leaves or continuous strips according to the kind of work to be performed.

Of course, it should be understood that, in the broader aspects of this invention, it is immaterial whether the lines of writing are produced as a result of a traveling platen or traveling type basket.

As in my copending application, Serial No.

579,390, impressions are produced on the under worksheets through transfer disks 16 carried by arms 17 mounted on a suitable support 18 at one side of the typewriter. The transfer disks each 5 have a central aperture 19 adapted to be placed over a finger or arm 20 and rest on a stud 21 on the carbon carrying arm 17. The disks are placed between the superposed worksheet strips and have their marginal portions located in the line 10 of writing, as shown in Fig. 3, so that the impressions of the type bars 13 will be reproduced on the under worksheets 15 through the medium of the disks. As the writing of a line progresses from one side to the other, relative movement is produced between the worksheet strips and the carbon arms, as by the traveling of the platen 10 with the carriage 11, and the disks 16 by frictional engagement with the worksheet strips at the line of writing rotate, presenting always a different portion of its surface to the line of writing.

20 As this rolling operation continues, and in accordance with the invention described and claimed in my copending application Serial No. 579,390, the carbon-carrying arm 17 is raised and lowered, thus causing the impressions to follow an undulating line in the working margin of the transfer strip as the disk rotates.

30 This is accomplished through the medium of an eccentric roller 22, see Fig. 3, mounted on an arm 23 which, with an arm 24, forms a frame 25 for the carbon arm 17. This is pivoted for movement on the support 18 about the axis of a screw 26, see Fig. 1. The roller 22 is provided with a ratchet 27 (see Fig. 9) which is engaged by a pawl 31 so that during the return movement of the platen to position to begin a new line the roller will be held against turning so that a new undulating line of impressions will start on the transfer disk at the beginning of the next line of writing. In this way, distribution of the impressions, and hence consumption of the transfer material carried by each disk 16, is distributed over a relatively wide circumferential margin of the disk.

40 In order to reduce the frequency with which the operator is required to remove the old disk and replace a fresh one, the disk should be made as large in diameter as conditions, such as the particular design of the typewriting machine, allows. It is practicable with most typewriters to have the disk of such diameter that its circumference would be greater than the length of the line of writing which could be performed on the typewriter.

50 If this were done, with the device as disclosed in my prior application, Serial No. 579,390, there would be left an unused portion or segment of the disk, the extent of which would depend upon the difference between the length of the line of writing and the circumference of the disk, so long as the disk remains between the worksheet strips, for the arcuate relation between the disk and the worksheets remains substantially constant regardless of the number of times that the platen travels in letter-feeding direction and is returned.

60 Moreover, should the carbon disk be lifted from between the worksheet strips for any reason and then be replaced therein, the previously unused portion of the disk might be brought into use with the result that the impressions of a part of the line of writing would be darker or heavier than the parts wherein the previously used portion of the disk is operating, thus resulting in unsightly work.

Again, the portion of the disk operating at the end of the line of writing would not be consumed uniformly because in typewriting all of the lines do not end at exactly the same place and, as a consequence, the ends of the exceptionally long lines in the carbon copies will be made with darker or heavier impressions, thereby accentuating the unavoidably unbalanced appearance of the page.

80 This unused segment of the transfer disk not only represents a loss in material, but makes it necessary for the operator to more frequently replace the disks, and if it were not otherwise avoidable it would be more economical to have the disk of a circumference equaling the length of the line of writing.

85 To avoid all these difficulties and disadvantages and yet permit a large transfer disk to be employed, the present invention provides means for holding the transfer disks against backward rotation during the return movement between the disks and the platen and work, so that the next line of impressions will always begin and proceed angularly around the disk from substantially the same point at which the last line of 100 impressions ended.

90 This is accomplished in the preferred form of this invention, which is the one illustrated herein, by providing the carbon-carrying arm 17 with means for gripping the disk and holding it against 105 backward rotation. This is conveniently done by providing on the finger 20 a tooth or projection 28 directed to the left and slightly bent to the rear and by providing each transfer disk with holes or other physical alterations 29 arranged in a circular line concentric with the bearing hole 19 and at such a distance from the center that they are capable of being entered by the tooth 28.

110 The tooth 28 is located below a semicircular 115 backing portion 30 of the carbon-carrying arm 17, and when a line is being written and the disk travels clockwise as viewed in Fig. 4, the tooth 28 flexes the material of the disk slightly to the rear as indicated in Fig. 8 but this does not retard its free rotation. When, however, the disk attempts to move counterclockwise, that is in the retrograde direction indicated by the arrow in Fig. 4, the tooth 28 enters one of the apertures 29 and holds the disk against movement. The 120 entrance of the tooth in the aperture 29 is assured by reason of the flexing of the lower end of the carbon disk 16 forwardly to the line of writing, as shown in Fig. 3.

125 Thus it will be seen that during return movements of the carriage, the transfer disk 16 is held against substantial rotation and as a result the next line of writing will begin at substantially the same angular position on the carbon disk as where the last line left off. This will continue around 130 the entire disk causing all portions of the disk to be utilized.

135 Of course, the first impression of the next line of writing seldom would occur at exactly the same point on the transfer disk as the last impression 140 on the previous line of writing because of the vertical movement of the disk under the influence of the eccentric roller 22 and because of some slight backward rotation which the disk may have before the tooth 28 enters the aperture 29. However, the consumption of the disk 28 will be continuous around its circumference and in an undulating line starting at an infinite number of points over a wide marginal band.

145 It has been found in practice that the annular 150

row of apertures 29 increases the flexibility of the disk and facilitates such flexion thereof as is shown in Fig. 3. The apertures 29, moreover, serve as pilot holes in the manufacture and processing of the disks.

Variations and modifications may be made within the scope of this invention and portions of the improvements may be used without others.

Having thus described the invention, what is claimed as new and for which it is desired to obtain Letters Patent, is:—

1. In a typewriting machine, a platen; type mechanism; a transfer disk adapted to roll between the worksheets superposed on the platen and in the line of writing during the letter-space relative movement between the worksheets and the type mechanism; a carrier for said disk; and means on the carrier and on the disk for holding the disk against rotation during return movements between the worksheets and the type mechanism.

2. In a typewriting machine, a platen; type mechanism; a transfer disk adapted to roll between the worksheets superposed on the platen and in the line of writing during the letter-space relative movement between the worksheets and the type mechanism; a carrier for said disk; and a ratchet and pawl connection between the carrier and disk for holding the disk against rotation during return movements between the worksheets and the type mechanism.

3. In a typewriting machine, a platen; type mechanism; a transfer disk adapted to roll between the worksheets superposed on the platen and in the line of writing during the letter-space relative movement between the worksheets and the type mechanism; a carrier for said disk; and a pawl on the carrier and a ratchet on the disk for holding the disk against rotation during return movements between the worksheets and the type mechanism.

4. In a typewriting machine, a platen; type mechanism; a transfer disk adapted to roll between the worksheets superposed on the platen and in the line of writing during the letter-space relative movement between the worksheets and the type mechanism; a carrier for said disk; and a projection on the carrier cooperating with a plurality of holes in the disk to hold the disk against rotation during return movements between the worksheets and the type mechanism.

5. In a typewriting machine, a platen; type mechanism; a transfer disk adapted to roll between the worksheets superposed on the platen and in the line of writing during the letter-space

relative movement between the worksheets and the type mechanism; a carrier for said disk; and a rigid arm on the carrier cooperating with a plurality of holes in the disk to hold the disk against retrograde rotation, the arm having a tooth directed toward said holes and the disk being flexed toward the arm when in manifolding relation with the worksheets so that the tooth enters one of said holes when the disk is given retrograde rotation.

6. An arm for holding a transfer disk between worksheets superposed on a platen in the line of writing, said arm having a bearing on which the transfer disk may be freely rotated as a result of the tractive engagement of the edge of the disk with the adjacent worksheet strips when the platen is moved in letter-feed direction; and means on the arm engaging the disk to grip the disk and prevent retrograde rotation of the latter during the return movements of the platen.

7. An arm for holding a transfer disk between worksheets superposed on a platen in the line of writing and having means adapted to grip the disk and prevent retrograde rotation of the latter, said arm having a tooth directed toward said disk and adapted to enter one of a plurality of holes in the disk when the disk is given retrograde rotation.

8. A transfer means for manifolding machines comprising a circular disk of transfer material having an aperture in the center forming a bearing about which it may be rotated; and a plurality of apertures placed in a circular line substantially concentric with the axis of the disk for the purpose described.

9. A transfer means for manifolding machines comprising a circular disk of transfer material having an aperture in the center forming a bearing about which it may be rotated; and a plurality of physical alterations placed in a circular line substantially concentric with the axis of the disk for the purpose described.

10. In a manifolding device for a typewriter having a cylindrical platen; means for rotatably supporting disks of transfer material between portions of superposed worksheets which are carried by the platen and located at the line of writing of the typewriter, said disks being rotated as a line is being written; means for automatically raising and lowering the transfer disks relative to the line of writing as the line is being written; and means for holding the transfer disks against retrograde rotation.

LOUIS C. ANTRIM.
